L. D. PIERCE

VEHICLE SIGNAL FACEPLATE

Filed April 21, 1922

Inventor,

L. D. PIERCE.

By *Sterling P. Buck,*
Attorney.

UNITED STATES PATENT OFFICE.

LEE D. PIERCE, OF FULTON, NEW YORK.

DESIGN FOR A VEHICLE SIGNAL FACEPLATE.

Application filed April 21, 1922. Serial No. 1,905. Term of patent 7 years.

To all whom it may concern:

Be it known that I, LEE D. PIERCE, a citizen of the United States, residing at Fulton, in the county of Oswego and State of New York, have invented a new, original, and ornamental Design for Vehicle Signal Faceplate, of which the following is a specification, reference being had to the accompanying drawing, forming part thereof.

The drawing is an elevation of the vehicle signal faceplate.

I claim:

The ornamental design for a vehicle signal faceplate, substantially as shown.

LEE D. PIERCE.
